UNITED STATES PATENT OFFICE.

ROBERT W. PAIN, OF NEW YORK, N. Y., ASSIGNOR TO AEOLIAN COMPANY, OF NEW YORK, N. Y., A CORPORATION OF CONNECTICUT.

TRACKER-BOARD.

No. 911,064.

Specification of Letters Patent.

Patented Feb. 2, 1909.

Application filed April 3, 1908. Serial No. 424,867.

To all whom it may concern:

Be it known that I, ROBERT W. PAIN, a citizen of the United States, residing at the city of New York, borough of Manhattan, county and State of New York, have invented certain new and useful Improvements in Tracker-Boards, of which the following is a specification.

This invention relates to improvements in tracker boards for pneumatic playing attachments for musical instruments, and the object of my invention is to provide a new and improved tracker board, which is simple in construction, is provided with two rows of holes, the number of holes in one row differing from the number of holes in the other row, and which tracker board is provided with means for readily adjusting it so that either one of these rows of holes becomes effective, and is reliable and effective in use.

In the accompanying drawings, in which like letters of reference indicate like parts in all the figures: Figure 1 is a transverse sectional view through my improved tracker board, in connection with the music rolls, showing it adjusted so that one row of holes is effective. Fig. 2 is a similar view showing the tracker board adjusted for making the other row of holes effective. Fig. 3 is a plan view, showing the rolls, perforated music sheet, and tracker, parts being broken away. Fig. 4 is a detail side view of the supporting plate for the ends of the movable part of the tracker board. Fig. 5 is a sectional view on the line b—b of Fig. 4. Fig. 6 is a face view of the outer edge plate of the adjustable part of the tracker board. Fig. 7 is a longitudinal view of the inner edge plate. Fig. 8 is an end view of the adjustable part of the tracker board, parts being omitted. Fig. 9 is a transverse sectional view through the fixed and adjustable parts of the tracker board. Fig. 10 is a side view of the frame of the adjustable part of the tracker board, showing the connections between the inner and outer plates of the adjustable part of the tracker board.

The adjustable part of my tracker board consists of an outer plate A extending longitudinally of the tracker board and an inner-plate B also extending longitudinally, the outer faces of both of said plates being curved convexly. These edge plates A and B are united at each end by cross pieces C secured to the inner faces of said edge

plates, which cross pieces C with the edge plates form the frame of the adjustable part of the tracker board. The side walls D of the adjustable part of the tracker board have beveled edges fitting in grooves in the inner faces of the plates A and B, whereby the covering members D are held in place, as shown in Fig. 9 for example.

In the outer plate A over which the perforated note sheets pass, there are two rows of tracker holes, one row F serving for the 88 note perforated music and the other row G for the 65 note music. The 88 note row F is provided with 91 holes of which 88 are only for sounding musical notes, one is used for controlling the loud pedal pneumatic and one at each end is for controlling the operation of an accenting mechanism. The 65 note row G has 67 holes of which the two at the ends serve for controlling the operation of the accenting mechanism. As will be seen from Fig. 7, the row F containing the 91 holes is shorter than the row G containing the 67 holes and thus it is evident that the holes for the 88 note sheet, as represented by the row F must be smaller and spaced closer than those of the 65 note row G. On the inner side of the tracker, that is, on the longitudinal edge plate B the conditions are reversed as all the holes are of the same size and therefore the row H of holes in the plate B corresponding to the row F in the plate A is much longer than the row J in the plate B corresponding to the row G of the plate A. The corresponding holes of the two rows in the plate B pertaining to the same note must be in line transversely to the tracker board as is shown at x—x and y—y in Fig. 6, this being practically the same at both ends, taking into consideration however the blank spaces a in the row J. It therefore follows that the ducts connecting the corresponding holes in the plates A and B must be arranged at an inclination or curved, but it would be practically impossible to bore these curved holes. I therefore connect the corresponding holes in the plates A and B by means of curved tubes K, properly secured on the plates so as to establish communication between the corresponding holes in the corresponding edge plates A and B. The side walls D merely serve as a covering to prevent the accumulation of dust and protect the tubes from injury while handling the tracker board.

The fixed section L of the tracker board is provided with a concave face of precisely the same curvature and radius as the plate B of the adjustable section and this fixed section 5 is covered by a metal plate M which fits snugly in this segmental recess. In the fixed portion there are two rows N and O of holes arranged precisely in the same manner and of the same size as the holes in the two 10 rows H and J of the edge plate B of the movable section and the holes of the rows N and O are so connected with a series of ducts P leading from the fixed section L that each two corresponding holes of the rows N and O 15 are connected with one and the same duct P. Of course it is to be understood that those ducts of the row N in the section L in excess of the number of ducts in the row O, are singly connected with ducts P of their own. 20 Each of these ducts P leads to the valve mechanism of a player pneumatic or to the mechanism for operating a pedal or an accenting mechanism. Those ducts P connected with corresponding holes in the rows 25 N and O of course operate only one of these mechanisms, as either of the two corresponding holes of the rows N and O, connected with any one duct P operate or cause the operation of the pneumatic mechanism connected with this duct P.

The movable section of the tracker board is provided at each end with a pivot Q which is so located that this section can swing on its pivots while describing the arc of the 35 outer face of the edge plate B and the arc of the concave recess in the face of the fixed portion L. These end pins Q pass through longitudinal slots R in plates S countersunk in the inner surfaces of the end walls T of the 40 tracker pit V, which is the box in which the tracker and music rolls W and Y are contained and the pivots Q project into recesses b¹ in the walls T.

Each plate S is provided with a U shaped 45 slot d near its inner edge and through said slot a pin g projects from the end of the movable part of the tracker and into a recess h formed in the wall T of the pit. A spring l suitably secured in the side wall of the pit 50 bears with its free end upon said pin g and thus these springs serve to press the convex surface of the inner edge plate B upon the convex surface of the fixed section L of the tracker board.

55 As shown in Fig. 1, the holes corresponding to the 65 note row G are in communication with the holes of the row J and ducts P the ducts of the row N being closed by a solid portion of the inner edge plate B. As 60 shown in Fig. 2, the movable section of the tracker board is differently adjusted and the holes of the 65 note row G are closed and the holes of the 88 note row F are now in communication with the holes of the row H and 65 ducts P, so that for the purpose of adjusting

the tracker for 65 note paper or 88 note paper it is only necessary to change the inclination of the movable part of the tracker board from the position shown in Fig. 1 to that shown in Fig. 2, or vice versa. For the purpose of so adjusting the tracker board the movable part is first pulled outward so as to remove the pins g at the ends of the movable section out of those legs of the U shaped slots d in which they rest and then the tracker 75 board is swung so as to bring these pins into the other legs of the slots d in which they are held by the spring l. The pins g with the edges of the slots d assure a correct position of the movable part of the tracker board for 80 either adjustment and prevent any displacement of the movable section of the tracker board after it has been adjusted and also hold the two sections of the tracker board in close contact so as to prevent any leakage of 85 air.

Having described my invention what I claim as new and desire to secure by Letters Patent is:—

1. A tracker board for pneumatic playing 90 attachments for musical instruments, composed of two longitudinal edge plates, each having rows of holes, cross pieces uniting the plates and tubes connecting the corresponding holes in the two plates, substantially as 95 set forth.

2. In a tracker board for pneumatic playing attachments for musical instruments, the combination with two longitudinal plates, each having two parallel rows of holes, there 100 being the same number of holes in each corresponding row of each plate and the two rows of holes in one plate being substantially the same length whereas in the other plate the two rows are of different length and tubes 105 connecting each hole of each row in one plate with the corresponding hole of the row in the other plate, substantially as set forth.

3. In a tracker board for pneumatic playing attachments for musical instruments, the 110 combination with two plates each having rows of holes, of cross pieces uniting the plates, tubes connecting the corresponding holes in the two plates and cover plates secured to the side edges of the said plates, 115 substantially as set forth.

4. In a tracker board for pneumatic playing attachments for musical instruments, the combination with two plates having rows of holes, of cross pieces uniting the plates, tubes 120 connecting the corresponding holes of the two plates, the plates being provided with grooves along their edges and cover plates having their edges held within the said grooves, substantially as set forth. 125

5. In a tracker board for pneumatic playing attachments for musical instruments, the combination with a fixed section having two rows of holes, of a movable section having ducts terminating at the edge of the movable 130

section adjacent to the fixed section in two rows of holes, the holes of each row being adapted to register with the holes of the corresponding row in the fixed section, pivots 5 on which the movable section can swing, which movable section is also movable toward and from the fixed section on a line extending in the direction from the outer to the inner face of the movable section, substantially as set forth.

6. In a tracker board for pneumatic playing attachments for musical instruments, the combination with a fixed section having two rows of holes, of a movable section having 15 ducts terminating at the edge of the movable section adjacent to the fixed section in two rows of holes, the holes of each row being adapted to register with the holes of the corresponding row in the fixed section, pivots 20 on which the movable section can swing, which movable section is also movable toward and from the fixed section on a line extending in the direction from the outer to the inner face of the movable section, and 25 means for pressing the movable section upon the fixed section, substantially as set forth.

7. In a tracker board for pneumatic playing attachments, the combination with a fixed section having two rows of holes, of a 30 movable section having ducts terminating at the edge of the movable section adjacent to the fixed section in two rows of holes, the holes of each row being adapted to register with the holes of the corresponding row in the fixed section, pivots on which the movable section can swing, which movable section is also movable toward and from the fixed section on a line extending in the direction from the outer to the inner face of the 40 movable section, and pins projecting from the ends of the movable section and springs bearing on said pins to hold the fixed section against the movable section, substantially as set forth.

45 8. In a tracker board for pneumatic playing instruments, the combination with a fixed section having two rows of holes, some of the holes, of one row being connected with holes in the other, a duct connected with each hole of one row not connected with a hole in the other row and a duct connected with each pair of connected holes of the two rows, a movable section having ducts terminating at the inner edge of said movable section in two rows of holes, each of which holes can register with a hole of one of the rows in the fixed section, the movable section movable toward and from the fixed section and also movable transversely to its 55 length and means for holding the movable section in contact with the fixed section at either lateral adjustment, substantially as set forth.

9. In a tracker board for pneumatic playing 60 attachments for musical instruments,

the combination with a fixed section having a concave face and two rows of holes and ducts communicating with the holes, said ducts terminating in the holes in the concave face of the fixed section, of a movable 70 section having a convex inner edge said movable section having ducts terminating in two rows of holes in said convex edge of the movable section, the convex edge being curved on the same radius as the concave 75 face of the fixed section, pivots on which said movable section can swing on the arc of said concave and convex adjacent faces, and plates in which said pivots are mounted, each plate having a slot extending in the 80 direction from the fixed section toward the movable section through which slots said pivots pass, substantially as set forth.

10. In a tracker board for pneumatic playing attachments for musical instruments, 85 the combination with a fixed section, having a concave face provided with two longitudinal rows of holes, of a movable section having a convex face fitting on the concave face of the fixed section, said movable section 90 having ducts that can register with the holes in the fixed section, end pivots on the movable section on which this section can swing, plates having slots through which said end pivots pass and move in the direction toward 95 and from the fixed section, said plates also having U shaped slots, pins projecting from the ends of the movable section through the U shaped slots, substantially as set forth.

11. In a tracker board for pneumatic playing attachments for musical instruments, the combination with a fixed section, having a concave face provided with two longitudinal rows of holes, of a movable section having a convex face fitting on the concave face of 105 the fixed section, said movable section having ducts that can register with the holes in the fixed section, end pivots on the movable section on which this section can swing, plates having slots through which said end 110 pivots pass and move in the direction toward and from the fixed section, said plates also having U shaped slots, pins projecting from the ends of the movable section through the U shaped slots, and means for locking said 115 pins in either leg of said slots, substantially as set forth.

12. In a tracker board for pneumatic playing attachments for musical instruments, the combination with a fixed section, 120 having a concave face provided with two longitudinal rows of holes, of a movable section having a convex face fitting on the concave face of the fixed section, said movable section having ducts that can register 125 with the holes in the fixed section, end pivots on the movable section on which this section can swing, plates having slots through which said end pivots pass and move in the direction toward and from the fixed section, said 130

plates also having **U** shaped slots, pins projecting from the ends of the movable section through the **U** shaped slots, and springs bearing on the pins to lock the pins in either 5 leg of the **U** shaped slots, substantially as set forth.

In testimony whereof, I have signed my

name to this specification in the presence of two subscribing witnesses, this 31st day of March 1908.

ROBERT W. PAIN.
